Primary Examiner — Mary Shannon Malley(74) *Attorney, Agent, or Firm* — Woodard Emhardt Henry Reeves & Wagner LLP(57) **CLAIM**

The ornamental design for a target stand, as shown and described.

DESCRIPTION

FIG. 1 is a perspective view of a target stand incorporating my new design, shown with environmental subject matter; FIG. 2 is a another perspective view thereof, shown with the environmental subject matter in an alternative configuration; FIG. 3 is a rear view thereof; FIG. 4 is a front view thereof;

FIG. 5 is a side view thereof seen from the right of the view in FIG. 4;

FIG. 6 is a side view thereof seen from the left of the view in FIG. 4;

FIG. 7 is a top view thereof;

FIG. 8 is a bottom view thereof; and,

FIG. 9 is a front view thereof, shown with the environmental subject matter in an alternative configuration.

The broken lines shown in the figures represent portions of the target stand that form no part of the claimed design.
